UNITED STATES PATENT OFFICE.

THOMAS J. DIXON, OF MADISON, WISCONSIN, ASSIGNOR TO LOVEJOY TOOL WORKS, OF CHICAGO, ILLINOIS, A CORPORATION OF ILLINOIS.

MULTIPLE EXPANDER.

1,417,980.

Specification of Letters Patent. Patented May 30, 1922.

Application filed March 23, 1921. Serial No. 454,715.

To all whom it may concern:

Be it known that I, THOMAS J. DIXON, a citizen of the United States, residing at Madison, in the county of Dane and State of Wisconsin, have invented a new and Improved Multiple Expander, of which the following is a specification.

My invention relates to certain new and useful improvements in multiple tube expanders of the type in which the shell is stepped and provided with sets of expanding rollers of corresponding diameters.

Heretofore in expanders of this type (see my Patent No. 1,379,087, dated May 24, 1921) the shoulders of the shell forming the steps are used as stops for the expander to keep it from creeping forward within the tube.

My invention has for its object to provide other means than these shoulders, especially in those expanders in which the increase in diameter from one step to the other is very slight or gradual.

In the drawings

Figure 1 is an elevation of one form of expander embodying the invention.

Figure 2 is a similar view of another form of the same.

Figure 3 is a cross section on the line 3—3 of Figure 1.

In the drawings in which like numerals and letters of reference indicate like parts in all of the figures, the expander shell consists of the parts 1, 2 and 3, constituting the several steps of the shell, the part 1 being of greatest diameter and the parts 2 and 3 of reducing diameters progressively, it being understood that there are as many parts or sections or steps to the shell as may be desired.

The shell is provided with pockets 4 for the rollers 5, the rollers being arranged in sets, one set for each step of the shell, the rollers also progressively increasing in diameter from the end of the shell of smallest diameter toward the end of largest diameter. The rollers 5 are placed into position by fitting them through the bore of the shell and are held against coming out radially by lips 7 in the usual way, a mandrel 6 being provided for forcing the rollers 5 radially outward for the usual purposes.

The roller pockets 4 of the several steps

may be arranged in staggered relation as shown in Figure 1 or in endwise alignment as shown in Figure 2, as may be found most convenient.

All of the foregoing construction of parts may be of the usual and ordinary construction and, per se, constitutes no part of the present invention.

Instead of using the shoulders formed by the meeting portions of adjacent shell sections as stops for the expander, I provide screws 9 which are tapped into bores 8 in the shell to the rear of the rollers adjacent thereto and the screws 9 may be provided with revolving thimbles 10 for reducing friction, if desired.

The screws 9 are threaded left handed when the expander feeds right handed, so that the feed of the expander will tend to tighten the screws rather than loosen them.

The largest section of the shell 1 alone may be provided with the stop screws 9 or each section may have bores 8 into which the stop screw can be placed accordingly as it is desired to use one or more of the expander sections.

By this construction, I am enabled to make an expander in which the increase in diameter from the smallest to the largest step can be very slight or gradual and yet provide means for stopping the forward feed of the expander in the tube at just the desired step and also enable the expander to be made without an abnormal diameter at the largest end.

From the foregoing description, taken in connection with the accompanying drawings, it is believed the complete construction, the manner of operation and the advantages of my invention will be readily understood by those skilled in the art to which it appertains.

What I claim is:

A tube expander comprising a stepped shell, a set of rollers for each step of the shell, said shell having roller receiving pockets, means for retaining the rollers in the pockets, a mandrel for engaging all of the rollers, said shell having threaded openings adjacent the rear extremity of the several sets of rollers and a stop screw adapted to be threaded into any one of said openings.

THOMAS J. DIXON.
